UNITED STATES PATENT OFFICE.

WILLIAM H. LEWIS, OF BIRMINGHAM, ASSIGNOR TO MALTBY, STEVENS & CURTISS COMPANY, OF HUNTINGTON, CONNECTICUT.

DESIGN FOR A SPOON AND FORK HANDLE.

SPECIFICATION forming part of Design No. 12,053, dated December 7, 1880.

Application filed August 17, 1880. Term of patent 14 years.

To all whom it may concern:

Be it known that I, WM. H. LEWIS, of Birmingham, in the county of New Haven and State of Connecticut, have invented new Design for Spoon and Fork Handles; and I do hereby declare the following, when taken in connection with the accompanying drawing and the letters of reference marked thereon, to be a full, clear, and exact description of the same, and which said drawing constitutes part of this specification, and represents a face view.

This invention relates to a design for the handle of spoons, forks, and similar articles; and it consists in the configuration as shown in the accompanying illustration.

About midway of the length of the handle is a round boss, *a*, projecting slightly at each side from the body of the handle, that is represented of greater diameter than the width of the body of the handle at that point. From the boss *a* the body of the handle expands slightly, and at its end intersects with a circle, *b*, which forms the tip; but at the point of intersection with the tip the body is con-

siderably less in width than the diameter of the tip, so as to form clearly-defined angles at the point of intersection. Around the edge of the body of the handle, from the boss upward and around the circular tip, is a bead. The face of the circle inside the bead is ornamented by a fan-shaped figure at each side, with an elliptical figure between them, all as shown in the accompanying illustration.

I claim—

The herein-described design for spoon and fork handle, consisting of the central circular boss, *a*, the circular tip *b*, the body between the boss and tip less in width at its intersection with the boss and tip than the diameter, respectively, of the boss and tip, forming clearly-defined angles at the point of intersection, the face of the circular end ornamented by a fan-shaped figure at each side and an elliptical figure between, as shown in the accompanying illustration.

WM. H. LEWIS.
